UNITED STATES PATENT OFFICE.

CARL A. KILGUS, CHESTER A. BURTON, AND GEORGE O. BERGMOSER, OF DETROIT,
MICHIGAN.

FUEL-OIL BURNER.

Application filed February 4, 1927. Serial No. 165,782.

Our invention relates to improvements in oil burners.

An object is to provide a simple, inexpensive oil burner such as is particularly adapted for use in house heating or the like wherein a mixture of fuel and steam is directed through a combustion space alongside a water boiler on to a target plate for combustion. This burner is so constructed and arranged as to function without the necessity of auxiliary blowers, atomizers, or other similar apparatus. The boiler is so associated with the burner as to furnish steam to be mixed with fuel in a mixing chamber to be directed therefrom upon the target plate. The fuel is conducted to the mixing chamber by a conduit leading through the water boiler in proximity to the side thereof which is adjacent to the combustion chamber and the steam is led to the mixing chamber so as to mix therein with the fuel delivered thereto and to eject the mixture therefrom to be directed against the target plate.

The boiler is preferably L-shaped, having an annular base, and the target plate superimposes the opening through the base so as to provide an air opening leading from such opening through the base upwardly about the periphery of the target. The upright portion of the boiler projects above the target plate and at a point sufficiently remote therefrom overhangs the same, and the mixing chamber is arranged in proximity to the upper overhanging end of the boiler superimposing the target plate at such a distance therefrom as to provide an intervening combustion space alongside the upright portion of the boiler.

Other distinct advantages and meritorious features of our improved fuel oil burner will more fully appear from the following description, appended claims and accompanying drawing, wherein:

Fig. 1 is a vertical sectional view through our improved burner.

Fig. 2 is a plan of our improved burner, and

Fig. 3 is a side elevation of the burner assembly.

In fuel oil burners it is highly desirable that the construction be simple and inexpensive, easily installed and easily operated, and that the construction be of such a character as to require the minimum amount of

care and attention on the part of the user. Our improved burner is intended to fulfill these requirements. It is here shown as installed in a furnace of a conventional type employed in house heating and indicated in dotted outline in Fig. 3.

We provide an L-shaped boiler 10, having an annular base 12 and an upright portion 14. A dished or saucer shaped target plate 16 superimposes the opening 18 through the base of the boiler and air openings 20 are provided to permit the air to flow upwardly around the margin of the target plate. The upright portion 14 of the boiler terminates in a dome-like structure which overhangs the base as appears in Fig. 1.

A mixing chamber 22 is disposed in proximity to the upper end of the boiler and communicates therewith through a conduit 24 to receive steam therefrom. Water is supplied to the boiler through a pipe 26 which leads from a tank 28 that may be supplied from a suitable source through a pipe 30. A float valve structure 32 may be employed to maintain a desired water level in the tank and likewise in the boiler.

Fuel oil is supplied to the mixing chamber by a pipe 34 which leads through the boiler, as appears in Fig. 2, in proximity to the inner surface thereof and discharges into the mixing chamber below the steam inlet to such chamber. This oil supply pipe leads from a suitable source not shown. There is preferably provided a thermostatically controlled valve 36 of any suitable construction to regulate the delivery of oil. The mixing chamber is provided with an outlet 38 disposed to direct the fuel mixture on to the target plate and such mixing chamber is arranged at such a height above the target plate as to provide a combustion space above such plate alongside the upright portion of the boiler. A baffle 40 may be employed to prevent the steam entering the mixing chamber from exerting a back pressure upon the oil supplied thereto.

To start the burner a suitable gas jet may be provided, gas being supplied through a conduit 42. The annular base of the boiler is here shown as provided with a trough 46 subjacent the periphery of the target plate 16, which trough has a waste pipe 44.

In the operation of this improved burner the fuel mixture is substantially volatilized at the time it leaves the mixing chamber and

is burned in passing through the combustion zone spreading outwardly from the periphery of the target plate. The burner operates continuously and efficiently without clogging or substantial carbonization.

What we claim is:

1. A fuel oil burner having a target plate, a water boiler having an annular portion spaced below said plate to permit air to flow therethrough and upwardly around the periphery of the plate and provided with an upright portion extending upwardly above said plate at one side thereof and in proximity thereto, a mixing chamber spaced above the plate and in proximity to the upper end of said upright portion of the boiler, said mixing chamber provided with an outlet to discharge a fuel mixture toward said target plate, a steam passageway leading from the boiler to the mixing chamber and a fuel passageway leading into the mixing chamber.

2. A fuel oil burner having an L-shaped boiler the base of which is provided with an air opening, a target plate superimposing said opening, a mixing chamber provided with a discharge outlet to direct a fuel spray toward said target plate, said mixing chamber spaced above the target plate and in proximity to the upper end of the upright portion of the boiler and communicating therewith whereby a combustion space is provided between the mixing chamber and the target plate and adjacent to the upright portion of the boiler, and a fuel conduit leading through said boiler into said mixing chamber.

3. A fuel oil burner having an L-shaped boiler provided with a ring shaped base, a saucer shaped target plate superimposing the opening through said base, the upright portion of said boiler projecting upwardly above the target plate and overhanging the same providing a combustion space alongside said upright portion above the target plate, a mixing chamber in proximity to the upper end of said upright portion of the boiler having a discharge outlet to direct a fuel jet on to said target plate, a steam passageway leading from the upper end of said upright portion of the boiler to the mixing chamber, and a fuel conduit leading through said boiler to said mixing chamber.

4. A fuel oil burner having an L-shaped boiler provided with an annular base and an upright portion terminating in a steam dome overhanging the base, a target plate superimposing the opening through the base, a mixing chamber in proximity to the upper end of said boiler superimposing said target and having an outlet to direct a spray of fuel against said target, a fuel conduit leading through the upright portion of the boiler to said mixing chamber, a fuel passageway leading from the upper end of said

upright portion of the boiler to said mixing chamber, and a baffle plate in said mixing chamber between said steam inlet and the fuel inlet.

5. A fuel oil burner having an L-shaped boiler provided with an annular base, a dished target plate superimposing the opening through said base, a mixing chamber in proximity to the upper end of the upright portion of the boiler superimposing said target plate and provided with an outlet to direct a fuel spray thereagainst, a steam passageway connecting the upper end of said boiler with the mixing chamber, a fuel supply pipe leading through the upright portion of the boiler in proximity to its inner wall and discharging into the mixing chamber below the steam inlet thereto, the top of said boiler shaped to provide an annular trough subjacent to the margin of said target.

6. A fuel oil burner having a boiler provided with an annular base and an upright portion at one side thereof, a target plate spaced above the opening through the base, a mixing chamber spaced above the plate and communicating with the upright portion of the boiler to receive steam therefrom, said mixing chamber provided with a nozzle to direct a fuel mixture toward the plate, a fuel pipe leading through the upright portion of the boiler to the mixing chamber, a source of water supply communicating with the boiler and means for maintaining a water level within the boiler substantially below the outlet therefrom leading to the mixing chamber providing a steam space within the boiler between the target plate and the mixing chamber and in proximity to the space therebetween.

7. A fuel oil burner having a boiler provided with an annular base having an upright portion at one side, a target plate spaced above the opening through said annular base and overhanging the same, said base so shaped as to form an annular trough spaced below the periphery of the plate, a mixing chamber spaced above the plate and communicating with the upright portion of the boiler to receive steam therefrom, a fuel conduit leading to said mixing chamber, said mixing chamber provided with a nozzle to direct a fuel mixture toward the plate.

8. A fuel oil burner having a boiler provided with an annular base having an upright portion at one side shaped to overhang the base, a target plate spaced above the opening through the base and overhanging the same, said base shaped so as to form a trough spaced below the periphery of the plate, a mixing chamber arranged at the upper and overhanging end of the upright portion of the boiler spaced above the plate and provided with a nozzle to direct a fuel mixture toward the plate, said mixing chamber

connected with the upper end of the upright portion of the boiler to receive steam therefrom, a fuel pipe leading through the upper portion of the boiler to the mixing chamber, said upright portion of the boiler arranged in proximity to the space between the mixing chamber and the plate to be heated by the combustion occurring therein.

9. In a fuel oil burner, an L-shaped boiler having a ring-shaped base and an upright portion overhanging the base, a target plate spaced above the opening through the base, a mixing chamber arranged in proximity to the upper overhanging end of the boiler and spaced directly above the target plate and

provided with a nozzle to direct a fuel mixture toward the plate, a fuel conduit leading through the upright portion of the boiler to the mixing chamber, said mixing chamber communicating with the upper end of the boiler to receive steam therefrom, and means for maintaining a water level within said boiler at or about the level of the plate with respect thereto.

In witness whereof we sign this specification.
